TELEVISION SYSTEM

Thomas T. Eaton, Haddon Heights, N. J., assignor
to Radio Corporation of America, a corporation
of Delaware

Application December 31, 1940, Serial No. 372,471

3 Claims. (Cl. 178—7.2)

This invention relates to television systems and more particularly to direct current voltage reinsertion to control the background of television images.

In television systems employing cathode ray tubes or other pickup devices of the type such as shown and described by Iams and Rose in an article entitled "Television pickup tubes with cathode ray beam scanning," published in the Proceedings of the Institute of Radio Engineers, August 1937, there is produced at the output of the pickup device a train of signals representative of the range of contrast of the picture being televised without the necessary direct current voltage component indicating whether the range of contrast is taken from a bright or dull picture. Under these conditions, the train of the picture signals representing a bright image will be similar to a train of signals representing a dull image having the same contrast as that of the bright image.

It is customary in the television art to reinsert the direct current voltage component which has been suppressed during transmission, as for example, where it is suppressed in the associated alternating current amplifier. These direct current voltage reinsertion circuits depend for their operation upon the transmission of periodically recurring control pulses which are caused to go to a fixed voltage level such as "black" in a picture. Such recurring pulses usually are the synchronizing pulses.

When, however, it is desired to reestablish the reference level to control the brightness of the image, which reference information the television pickup tube does not convey, it is necessary to control the amount of reinserted direct current voltage in accordance with the average brightness of the televised object.

Bedford Patent 2,192,121, patented February 27, 1940, shows and describes one system and method for reestablishing the desired background control direct current voltage component.

It very often becomes desirable to manually control the background independently of automatic control furnished by the average illumination of the scene being televised. Furthermore, it is desirable that both manual and automatic control function at the same point in the system.

According to this invention, there is provided a light sensitive device adapted to produce a voltage dependent upon the average brightness of the object being televised and cause this voltage to control a clipper tube in the amplifier

5 of the video signal channel. Furthermore, a manual control means completely independent of the automatic control means is provided, whereby there is an independent manual and automatic control to maintain a reference in the train of picture signals depending upon the average brightness of the televised object.

The primary object of this invention is to improve the image representation of a transmitted 10 video signal.

Another object of this invention is to provide a video signal with a reference component whereby the transmitted signal is representative of the average brilliance of the televised object.

15 Still another object of the invention is to provide an improved automatic and manual background control.

Other and incidental objects of this invention will be apparent to those skilled in the art from the following specification considered in connection with the accompanying drawing, in which

20 Figure 1 is a block and circuit diagram showing a television transmission system utilizing one form of this invention;

Figure 2 is a circuit diagram showing another form of this invention; and

Figure 3 is a circuit diagram showing still another form of this invention.

Referring now in more detail to Fig. 1, there is shown a pickup camera 1 which may be of the type such as described by Iams and Rose in an article entitled "Television pickup tubes with cathode ray beam scanning," published in the Proceedings of the I. R. E., August 1937, which supplies a train of picture signals representative of the image on the film 3 under scansion to an amplifier 5 which, in turn, supplies the amplified video signal to the control electrode 7 of an amplifier tube 9 through coupling condenser 11.

40 A light sensitive device 13 is mounted adjacent the film 3 in order to collect light from a source 15 through the film 3 whereby there will be produced a control signal from the light sensitive device representative of the average brightness 45 of the image on the film 3. This signal is applied to the control electrode 17 of the tube 19 through a potentiometer 21 which is provided as a manual adjustment of the amount of control signal required. A bias supply voltage for the light sensitive device 13 is supplied through the potentiometer 23 which is connected to any suitable power source.

50 The tube 19 also includes a cathode 22 and an anode 23. The cathode circuit includes a re-

sistance 25 and a resistance 27 connected in series. The anode 23 is connected directly to a source of positive potential.

The amplifying tube 9 includes a cathode 29 and a cathode resistor 31 which is connected in series with a condenser 33. The control electrode 7 is connected in series with a control electrode resistor 35 which is in turn connected to the variable tap of a potentiometer 37 which serves to manually control the bias potential on the control electrode 7. The output circuit of the tube 9 includes the anode 39 which is connected to the transmitter 41 through a coupling condenser 43. The anode 39 is supplied with a positive potential through the anode resistor 45 and a series peaking coil 47.

The operation of the circuit will now be more fully described. As a motion picture film 3 passes through the projection apparatus, an image thereof is projected on the light sensitive mosaic element of the television camera 1. This produces charges upon the element (in a well known manner) and by scanning the element a train of picture video signals representative of the optical image may be developed. These signals are then amplified in the amplifier 5 and applied to the control electrode of the clipper tube 9.

The average film brightness responsive system including the light source 15 and the light responsive device 13 is located at such a position that the average brightness of the image being televised from the film 3 will produce in the average light responsive circuit a signal whose amplitude is dependent upon the average brightness of an adjacent image or the same section of the film 3 being televised. The film preferably moves in the direction of the arrow so that the control signal produced will anticipate the corresponding picture signal train by a small amount equal to the time it takes the film to move from the control gate to the picture gate. This allows the time delayed control circuit to be ready for the picture signal. This control voltage is applied to the control electrode 17 of the tube 19 in such a polarity that when the image being televised from the film 3 is bright a less positive voltage is applied to the control electrode 19. A less positive voltage on the control electrode 17 will cause the cathode follower 22 to go less positive whereby the connection between the cathode 22 and the cathode 29 causes the cathode 29 also to go less positive.

When the cathode 29 goes less positive it causes a greater average current to flow through the amplifying tube 9 and thus establishing a greater output signal for a bright picture which necessarily results in a reestablishment of the reference voltage in the picture signal which is lost by the pickup camera 1.

It follows that when there is a dull or less bright image on the film 3 the control electrode 17 goes more positive whereby the cathode follower 22 goes more positive and causes the cathode 29 also to go more positive whereby the differential between the cathode 29 and the control electrode 7 is increased thus allowing less current to flow through the amplifier tube 9 which results in a signal having a lower average amplitude than in the case of a bright image.

The bias on the control electrode 7 may be independently controlled by manually varying the adjustment of the potentiometer 37. By providing the manual adjustment in the control electrode circuit of the tube 9 this adjustment may be changed without in any way affecting the

automatic adjustment which is maintained through the cathode circuit of the tube 9.

The change in the adjustment of the potentiometer 37 in no way affects the incoming video signals from the amplifier 5.

Fig. 2 shows another form of this invention wherein like numerals refer to similar parts. The light sensitive device 13 is supplied with its polarizing potential through a relatively large resistance including resistances 25, 27 and 49 which is included in the cathode circuit of the tube 19. A resistance 51 is connected to a source of positive potential and to the junction between resistances 25 and 49 and to the resistance 21.

It therefore follows that the potential drop across the resistances 49 and 27 caused by the positive potential applied thereto through resistance 51 is also applied to the photocell 13 through the resistance 21.

This, however, has no effect upon the functioning of the control circuit because the control potential from the cathode 22 of the tube 19 is applied to the control electrode 29 of the tube 9. It is desirable to maintain this potential somewhat above the saturation of the light sensitive device 13 so that no fluctuation in potential applied thereto will cause a change in the sensitivity of the light responsive device 13.

Fig. 3 shows another form of this invention in which an additional amplified tube is included in the circuit to provide flexible adjustment and general overall stabilization. There is furthermore provided still another method of obtaining polarizing potential for the light sensitive device 13.

A resistance 53 is provided in the cathode circuit of the tube 55 to stabilize the amplifier circuit by degeneration and also to supply bias to tube 55. A potentiometer 56 is shunted with a voltage source to supply bias potential to the control electrode 59. The output signal from the tube 55 is applied to the control electrode 17 of the tube 19 which functions in this form of the invention in a manner similar to that previously described.

It will be noted that a direct current amplification connection is made between the output of tube 55 and tube 17 in order to pass the lower frequency necessary for the proper functioning of this control circuit.

In this form of the invention the tube 9 is supplied with the video signal in a similar manner as that shown and described in Fig. 1. The manual control is obtained through the variation of the potentiometer 37 and in this form of the invention operates independently of the automatic control which is supplied from the control tube 19.

Although there has been shown a pickup device for transforming images on a film to a train of signals representative thereof, this invention may be applied to the pickup of any type of television scenes and furthermore the background may be controlled manually and independent of the automatic control which may or may not be utilized at the discretion of the operator.

While several systems for carrying this invention into effect have been indicated and described, it will be apparent to one skilled in the art that this invention is by no means limited to the particular organizations shown and described, but that many modifications may be made without departing from the scope of this invention as set forth in the appended claims.

I claim as my invention:

1. In a television transmitting system, a scan-

ning device for developing picture signals, an amplifier for said picture signals including an amplifying tube having a cathode, a control electrode and an anode, means including a light responsive device for developing a signal wave whose amplitude varies in accordance with occurring variations in overall brilliancy of the object being scanned, means for applying said picture signal between said control electrode and a point of fixed potential, means for applying said signal wave between said cathode and said point of fixed potential to automatically control the conductance of said amplifying tube in accordance with occurring variations in the overall brilliancy of said object, and means to manually control the bias potential between said control electrode and said point of fixed potential independently of said automatic control.

2. In a television signal transmitting system including a scanning device for developing picture signals representative of an object being scanned, and an amplifier for said picture signals including an amplifying tube having a cathode, a control electrode and an anode, means for providing background control of the transmitted image including means for developing a signal wave whose amplitude varies in accordance with occurring variations in overall brilliancy of said

object, means for applying said signal to said cathode through a cathode resistor connected between said cathode and a point of fixed potential, and means for manually varying the bias potential on said control electrode independently of the potential of said cathode.

3. In a television signal transmitting system including a scanning device for developing picture signals representative of an object being scanned and an amplifier for said picture signals including an amplifying tube having a cathode, a control electrode and an anode, means for providing background control of the transmitted image comprising, in combination, a manual control for varying the bias potential on said control electrode, a light sensitive device for developing a control signal whose amplitude varies in accordance with occurring variations in overall brilliancy of said object, a control tube having a cathode and an input circuit including said light responsive device, a cathode resistor connected to a point of fixed potential and common to said amplifying tube and said control tube cathodes to transmit said control signal to said amplifying tube independently of said picture signal and said manual control of the bias of said amplifying tube.

THOMAS T. EATON.
